UNITED STATES PATENT OFFICE.

CHARLES HENRI JACOB, OF LYONS, FRANCE.

APPARATUS FOR APPLYING FINISHING SUBSTANCES TO COTTON FABRICS.

SPECIFICATION forming part of Letters Patent No. 605,434, dated June 7, 1898.

Application filed November 14, 1896. Serial No. 612,125. (No model.) Patented in France July 17, 1896, No. 258,123; in England October 22, 1896, No. 23,499; in Italy October 22, 1896, LXXXIV, 482; in Switzerland November 10, 1896, No. 13,313, and in Belgium December 5, 1896, No. 124,964.

To all whom it may concern:

Be it known that I, CHARLES HENRI JACOB, manufacturer, a citizen of the Republic of France, residing at Lyons, in the Republic of France, have invented an Apparatus for Applying a Finishing Substance to Cotton Fabrics, (for which I have obtained Letters Patent in France, No. 258,123, dated July 17, 1896; in Switzerland, No. 13,313, dated November 10, 1896; in Belgium, No. 124,964, dated December 5, 1896; in England, No. 23,499, dated October 22, 1896, and in Italy, Vol. LXXXIV, No. 482, dated October 22, 1896,) of which the following is a specification, reference being had to the accompanying drawings.

This invention relates to an improved apparatus for applying a dressing, of which hait-thao or vegetable gelatine, also known as "gelose," is the chief ingredient, to single-thread cotton.

The machine is represented in the accompanying drawings, Figure 1 being an elevation of its left-hand portion; Fig. 1^a, a similar elevation of its right-hand portion; Fig. 2, a plan of its left-hand portion, and Fig. 2^a a plan of its right-hand portion. Fig. 3 is a longitudinal sectional view of part of the drier, showing the supports for the threads.

It consists of the following main parts: Its frame is constructed in two parts B B', connected on both sides by longitudinal side frames or cheeks F F. These support a heated drier S, within which the cotton yarn is to circulate and to be dried. The drier consists of two parts, one lower stationary part, connected at the bottom with a source of heat, and an upper portion in the shape of a removable cover H, adapted to be raised when required—that is to say, when it is necessary to tie the ends of broken threads while the machine is in operation—by means of balanced weights E, sliding along the discharge-chute D. As shown in Figs. 1 and 1^a, this discharge chute or exhaust D is also formed in two parts, which fit and are adapted to slide within each other, the upper stationary part being supported in any suitable manner,

while the lower part is joined on centrally to the movable top of the cover H. It is necessary to adapt the two parts thus to slide (or telescope) upon each other, as will readily be understood, first, in order to permit the cover H of the drier S to be lifted when it is required to rejoin the parts of broken threads; secondly, for the purpose of effecting the constant admission and discharge by suction of the hot gases through the top part of the stationary chimney, and, lastly, upon the fixed portion of this drier S there is secured a plate I, having perforations formed all over its surface which serve to maintain a constant heat and uniformly and without pressure to distribute the same over the whole area of the yarn passing through. The cotton yarn, during its passage through the said drier H S, is sustained by supports X X' X^a, secured at predetermined distances apart and alternately upon the plate I and the bottom part of the movable cover H.

The supports or guides for the threads are constructed in the following manner: Upon the bottom of the lid H and the top of the perforated plate I are arranged cross-pieces m m, the object of which is to insure the rigidity of the lid and of the plate, and to these cross-pieces are attached the supports x x' x^a by means of bolts or rivets or in any other suitable manner. These supports carry at one of their extremities, mounted upon a spindle, a small cylinder or roller p, upon which the thread passes. The object of these supports is to guide the threads and to prevent them from swaying about inside the drier. When the lid H is raised, the upper supports, fixed thereto, move with it and cease to bear upon the thread, while the lower supports remain constantly fixed. The threads may thus be joined in the event of their breaking.

The reeling-bobbins which contain the cotton yarn to be dressed are placed upon a movable frame C, mounted upon the left-hand portion B of the main supporting-frame of the machine. Adjacent to this frame C there is arranged a dressing trough or bath A, hav-

ing a double bottom between the two surfaces of which there passes a steam-pipe which serves to keep the dressing-bath constantly tepid. It is in this bath that the 5 novel dressing, with hai-thao for its main constituent, is contained, and into it the cotton threads are made to dip, after which they leave it and are conducted through a series of guides *a*, whence they pass through a 10 transverse row of drainers *P*, whereupon they enter the drier *S*, in which as they pass through they are dried. Upon completing their passage through the said drier, and being consequently sufficiently dried, they have in the 15 last stage of operation to be simply wound upon bobbins. The winding apparatus employed in effecting this consists of a number of winding drums or rollers *T*, which by frictional contact set the receiving-bobbins *R'* in 20 rotary motion. Upon these bobbins each row of dressed and dried threads are wound evenly by means of thread-guides *G*, to which an ordinary reciprocating motion is imparted. The winding-drums *T* receive motion from the 25 friction-pulley *Z* and feeding-plate *Z'*.

Having thus described the construction of the machine, it now remains for me to state the manner in which the yarn is dressed.

The cotton yarn, whether dyed or bleached, 30 or not, after having been wound upon the bobbins *R* passes into the bath or trough *A*, containing the finishing substance, there to be dressed, and thence issues through a species of draw-plate or guide *a*, which serve to make 35 the nap or pile closely adhere to the surfaces of the threads, and thereby to render these perfectly cylindrical. The yarn then passes onto the drainer *P*, in being conducted over which it is freed from any dressing it may 40 carry with it in excess of what is required, the sizing being at the same time completed by the aid of gentle pressure. The next step is to convey the yarn into the drier through eyes arranged horizontally for the purpose. 45 In traveling through this arrangement it is gradually dried, equidistant supports *X*, *X'*, and *X''* being provided throughout the length of the drier, and upon leaving the drier the threads are finally wound upon the bobbins 50 *R'* by means of guides *G*, adapted to perform a variable or adjustable reciprocating motion.

While the finishing substance designed to be used in this apparatus is one in which 55 hai-thao or gelose forms a principal ingredient, the apparatus described is of course susceptible of use with any preferred dressing compound to be applied to single-thread cotton.

I may mention, in conclusion, that tepid dressing only should be applied to the threads, which, in receiving such dressing, should be slightly moist.

Having described my invention, what I claim is—

65 1. In an apparatus for sizing cotton thread,

the combination with a frame carrying at one end suitably-supported bobbins of thread and sizing apparatus therefor, and at its other spool-winding mechanism, of a drier for the threads comprising a vessel having a heater 70 therein, a cover removably secured to said drier a perforated plate arranged over the heater and beneath the cover, and thread-guides arranged between said cover and plate, substantially as described. 75

2. In an apparatus for sizing cotton thread, the combination with a frame carrying at one end suitably-supported bobbins of thread and sizing apparatus therefor, and at its other spool-winding mechanism, of a drier for the 80 threads comprising a vessel having a heater therein, a cover removably secured to said drier, a perforated plate arranged over the heater and beneath the cover, thread-guides arranged between said cover and plate, and 85 means for supporting said threads in their passage through the drier, substantially as described.

3. In an apparatus for sizing cotton thread, the combination with a frame carrying at one 90 end suitably-supported bobbins of thread and sizing apparatus therefor, and at its other spool-winding mechanism, of a drier for the threads comprising a vessel having a heater therein, a cover removably secured to said 95 drier, a perforated plate arranged over the heater and beneath the cover, thread-guides arranged between said cover and plate and means for supporting and guiding said threads in their passage through the drier comprising 100 wheels or rollers suitably supported on the inner surface of said cover and plate, the wheels carried by the cover being above, and those carried by the plate below the plane of travel of the threads through the drier, sub- 105 stantially as described.

4. In an apparatus for sizing cotton thread, the combination with a frame carrying at one end suitably-supported bobbins of thread and sizing apparatus therefor, and at its other 110 spool-winding mechanism, of a drier for the threads, means for conducting the threads therethrough, a cover removably secured to said drier, and counterbalance mechanism connected with the cover for raising the same, 115 substantially as described.

5. In an apparatus for sizing cotton thread, the combination with a frame carrying at one end suitably-supported bobbins of thread and sizing apparatus therefor, and at its other 120 spool-winding mechanism, of a drier for the threads, means for conducting the threads therethrough, a cover removably secured to said drier, a telescoping escape-flue carried by the cover and counterbalance mechanism 125 connected with the cover for raising the same, substantially as described.

6. An apparatus for sizing cotton thread comprising, in combination, a hinged frame carrying a plurality of bobbins on which the 130

thread is wound, a sizing device, drainers for removing the surplus sizing after the threads leave said vessel, a drier, comprising a vessel having a heater therein, a cover removably secured to said drier, a perforated plate arranged over the heater and beneath the cover, thread-guides arranged between said cover and plate, and spool-winding mechanism for

winding the threads after they leave the drier, substantially as described.

In testimony whereof I have hereunto set my hand this 26th day of October, 1896.

CHARLES HENRI JACOB.
